ELECTRONIC TIMING APPARATUS

William Henry Bruns, Lincolndale, N. Y., and Harold Edward Galanty, Hillside, N. J., assignors to Otis Elevator Company, New York, N. Y., a corporation of New Jersey

Application June 24, 1944, Serial No. 541,972

9 Claims. (Cl. 250—27)

1

The invention relates to electrical timing apparatus, especially for effecting plural timing operations.

There are various applications for plural timing in which it is desired that individual timing operations be consummated in the same sequence as initiating operations. In the copending application of Gavin Watson, William Henry Bruns and Harold Edward Galanty, filed June 24, 1944, Serial Number 541,970, for example, calls registered by hall buttons of an elevator system which have remained unanswered for more than a certain length of time are given certain preference. In one mode of application, preference is given these calls by causing them to be answered as timed calls in the order in which the calls were registered. This involves rendering only one of these calls effective at a time.

It is of advantage in electrical timing circuits to employ electronic tubes, especially grid controlled gas filled tubes. In effecting plural timing operations, such as in the Watson et al. application, it is desirable to have like apparatus for each of the various individual timing operations, so that in employing electronic tubes, each individual circuit is provided with an electronic tube controlled so that it may be rendered conductive after the expiration of a certain time period after an initial control operation.

The object of the invention is to provide electrical timing apparatus for plural timing operations in which each individual timing circuit employs an electronic tube and in which firing of the tubes is controlled so that only one tube is conductive at a time and so that the tubes are rendered conductive in the order in which control operations for the tubes are initiated.

In carrying out the invention, according to the arrangement which will be described, each individual timing circuit is provided with a condenser which is connected across the grid-cathode circuit of the tube. The condensers are charged to a voltage value to prevent the firing of the tubes. The time interval of each individual timing circuit is initiated by a control operation which initiates the discharge of the condenser. The condenser discharge is effected gradually and when the condenser voltage is reduced to a certain value the tube fires. A resistance is arranged in the plate circuits of the tubes in a feed wire common to the cathodes. When a tube fires, the potential drop across this resistance changes the potential of the cathodes of the other tubes with respect to grids, to prevent the firing of these tubes. Capacitance is

2

employed to delay the decrease of potential drop across this resistance when a tube ceases conducting. This causes the firing of the tube the control operation for which occurred next, which upon firing blocks the other tubes as before. Thus the firing of the tubes in the order of initiation of the respective control operations is assured.

In the specific arrangement of circuits illustrated, alternating current voltage is applied to the plate circuits of the tubes to enable the tubes to be shut off. Also, alternating current voltage is superimposed on the condenser voltage applied to the grid-cathode circuit of each tube. The phase relationship of this superimposed grid-cathode voltage with respect to the plate voltage is such as to render the tube initially conductive near the beginning of the positive portion of a plate voltage cycle.

Features and advantages of the invention will be seen from the following description and appended claims.

The figure of drawing is a wiring diagram of electrical timing circuits for a plurality of timing operations in accordance with the invention.

The circuits are taken from Figure 4 of the aforementioned copending application of Watson et al. as illustrative of an application of the invention. In the specific arrangement shown in the Watson et al. application, push buttons termed hall buttons are arranged at the landings of an elevator system and act through floor relays to control the operation of a plurality of elevator cars. An up hall button and a down hall button are provided at each intermediate landing and the down floor relays through which the down hall buttons register calls are provided with contacts to control the timing apparatus. A seven floor installation is shown and these contacts of the down floor relays are provided for the second, third, fourth, fifth and sixth floors. The floor relays for these floors are designated 3D, 4D, 5D and 6D respectively and the particular contacts of the floor relays utilized to control the timing apparatus are designated 3, this numeral being appended to the characters employed for the floor relays, as for example contacts 2D3 of the down second floor relay.

A source of direct current is provided for the timing apparatus, the supply lines of which are designated + and -. Certain parts of the timing apparatus are individual to the respective floors and certain parts are common to the floors. It is preferred to arrange most of this timing apparatus as a unit and to enclose it, as indicated

by Y, to seal it against moisture and dirt and to shield it against extraneous electrostatic and electromagnetic effects.

The circuits individual to the respective floors are the same for each floor. Referring for example to the circuits for the second floor, the time interval is obtained by the discharge of a condenser designated 2C. 2R is a discharge resistance for the condenser. The condenser acts through an electronic tube 2CT, hereinafter referred to as a controlled tube. The circuits are particularly adapted for the utilization of a hot cathode controlled tube which is prevented from firing by a negative grid voltage provided by the charge on condenser 2C. However, other types of controlled tubes may be employed. The anode of the controlled tube is designated 2AN, the cathode 2CA and the grid 2GR. 2SG is a shield grid which is connected to the cathode. However, tubes without shield grids may be employed. 2IT is a two element tube arranged in the condenser charging circuit and will hereinafter be termed an isolating tube. 2R1 is a current limiting resistance in the condenser charging circuit, the purpose of which will be seen as the description proceeds. 2R3 is a resistance in the circuit for the control grid 2GR, the purpose of which will be seen from later description. Contacts 2D3 on the down second floor relay are provided in these circuits but are external to the unit Y. These contacts when closed complete an auxiliary discharge circuit for the condenser, this circuit also including the isolating tube 2IT. An electrical load is in the plate circuit of the controlled tube so that the tube may be connected across the direct current supply lines. This load is illustrated as the coil of an auxiliary time relay 2TR. Connected across the coil of relay 2TR is a condenser 2C2 and resistance 2R2, the purpose of which will be explained later. Contacts of the auxiliary time relay are not shown. The corresponding elements of the individual circuits of the unit for the other floors are similarly designated, differentiation being had as to floors by numerals corresponding to floor numbers which precede the designating letters.

As to the circuits common to the various floors, TP is the primary winding of a transformer supplied externally of the unit from a source of alternating current designated AC. TS1, TS2, TS3 and TS4 are secondary windings of this transformer. Secondary windings TS3 and TS4 are for supplying alternating current to the full wave rectifier REC. This rectifier provides direct current for the charging of condensers 2C to 6C inclusive. Filter condenser C8 and load resistance R8 are connected in parallel across the output supply lines RE+ and RE- from the rectifier. Transformer secondary winding TS2 is utilized to supply current to the heater elements of controlled tubes 2CT to 6CT inclusive. For convenience, the heater elements and connections to this secondary winding are not shown.

Alternating current voltage is superimposed on the direct current voltage applied to the plate circuits of the controlled tubes. This superimposed alternating current voltage is provided by transformer secondary winding TS1. The value of this superimposed voltage with respect to the direct current voltage applied to the plate circuits is such as to cause the resultant voltage applied to the tubes to be negative for a fraction of a cycle. This provides positive voltage for a major portion of the cycle and yet enables the grid of each tube to retain control to shut off the tube.

Combined alternating and direct current voltage is of advantage for the plate circuits in that it enables the use of standard direct current switches in the plate circuits. However, alternating current voltage alone may be applied to the plate circuits. Alternating current voltage provided by transformer secondary winding TS1 is also superimposed on the direct current voltage provided by condensers 2C to 6C inclusive in the control grid circuits of the corresponding controlled tubes. Condensers C3 and C4 and resistances R3 and R4 constitute a phase shift network for controlling the phase relationship of the superimposed alternating current grid voltage with respect to the plate voltage.

TC is a manually operable time control switch which acts in conjunction with resistances R1 and R2 to effect the common control of the time interval for all individual circuits. R7 is a protective resistance for isolating tubes 2IT to 6IT inclusive. Resistance R9 is a loading resistance for the cathodes of the controlled tubes and is arranged in the plate circuits of these tubes on the cathode side in a wire common to the cathodes. Condenser C9 is for delaying the decrease in potential drop across resistance R9 when a controlled tube is shut off. SE1 and SE2 are service switches for connecting in the timing apparatus for operation.

When power is applied to lines + and - a charge is caused to be built up on condensers 2C to 6C inclusive to cause negative potential to be applied to the control grids of the controlled tubes sufficient to block the tubes. This is effected by connecting each of the condensers in series with its discharge resistance across resistances R4 and R5. Resistances R4 and R5 in conjunction with resistance R6 constitute a potentiometer resistance connected from line + through transformer secondary winding TS1 to line -. As there is no alternating current voltage in secondary winding TS1 due to switch SE2 being open, direct current voltage is applied to the condensers. The relative ohmic values of these resistances are such that sufficient voltage is applied to the condensers to build up sufficient charge to prevent the firing of any controlled tube, should a floor relay be operated when switches SE1 and SE2 are closed, until sufficient time has elapsed to heat up the cathodes. This prevents disintegration of the cathodes. The amount of voltage applied to the condensers is not sufficient to cause break-down of the isolating tubes 2IT to 6IT inclusive which are connected across the corresponding condensers through resistances 2R1 to 6R1 inclusive respectively and resistances R8 and R7.

Upon the closing of service switches SE1 and SE2 the timing apparatus is rendered effective for operation. The closing of switch SE1 short-circuits resistance R5 to superimpose the alternating current voltage from the phase shift network onto the condenser voltages. The closing of switch SE2 connects the primary winding TP of the transformer to the alternating current source. Secondary windings TS3 and TS4 cause rectifier REC to apply direct current voltage to supply lines RE+ and RE-. The value of this voltage is sufficient to cause break-down of isolating tubes 2IT to 6IT inclusive to effect the further charging of the condensers. Taking condenser 2C, for example, as the condenser charge builds up the potential drop across isolating tube 2IT decreases until extinction value is reached whereupon the tube goes out. The condenser then starts to dis-

charge by way of discharge resistance $2R$ and resistance $R4$ until, due to the lowering of the condenser charge, the voltage applied to the isolating tube rises to a point sufficient to break down this tube. This recharges the condenser to a value to cause the isolating tube to extinguish. This cycle of operation is continuously repeated and may be termed a discharge, recharge cycle.

Before discussing sequence timing, the effect on an individual timing circuit of the closing of the corresponding floor relay contacts will first be described. For this condition, the effect of resistance $R9$ will not be considered. Continuing with condenser $2C$ as example, upon the closure of contacts $2D3$, the auxiliary discharge circuit for the condenser is completed. This circuit is through resistance $R7$. At the same time resistance $2R1$ is connected across the lines $RE+$ and $RE-$. Regardless of the point on the condenser discharge, recharge cycle that this occurs the potential drop across the condenser is sufficient to cause the isolating tube to break down. The current flow is in a direction opposite to that for charging the condenser and, owing to the fact that resistance $R7$ is of low ohmic value, the condenser discharges immediately to the value of the extinction voltage of the isolating tube. As this point is reached, the isolating tube goes out and the condenser now discharges into discharge resistance $2R$ and resistance $R4$. Owing to the high ohmic value of resistance $2R$, this discharge takes place slowly, the rate depending upon the value of this resistance. Should the call be answered and therefore contacts $2D3$ separate before the condenser has discharged sufficiently to reduce the negative potential on the control grid to a point to unblock the tube, the condenser immediately recharges and continues its discharge, recharge cycles.

Assume that the call is not answered and contacts $2D3$ do not separate before the condenser has discharged sufficiently to reduce the negative potential on grid $2GR$ with respect to cathode $2CA$ to a point to unblock the tube. When this point is reached, the tube fires during the positive portion of the next cycle of the voltage applied to the plate circuit of the tube and continues to conduct during this portion of each succeeding cycle. The phase relationship of the alternating current voltage superimposed on the condenser discharge voltage with respect to the voltage applied to the plate circuit of the tube is such as to cause the tube to conduct near the beginning of the positive portion of each cycle of plate voltage. This arrangement causes the tube when it becomes conductive to pass sufficient current to cause operation of relay $2TR$, the coil of which is the plate circuit. Upon the subsequent separation of the floor relay contacts, the condenser is recharged and, upon the potential of the grid becoming negative with respect to the cathode a certain amount, the tube is shut off by the action of the alternating current voltage applied to the plate circuit. Condenser $2C2$ in parallel with the coil of relay $2TR$ is to obviate the effect of the inductance of the coil and thus retain the negative portion of the cycle of applied voltage. This insures the tube being shut off when the floor relay contacts separate. Resistance $2R2$ serves as a current limiting resistance for the condenser.

In order that the above described operations may be more clearly understood, assume that the direct current voltage of lines $+$ and $-$ is 110 volts, that the peak value of the alternating cur-

rent voltage superimposed thereon by transformer secondary winding $TS1$ is 141 volts, and that indirectly heated hot cathode controlled tubes having characteristics suitable for these voltages and a critical grid voltage of approximately -2 volts are utilized. Also assume that the potential across lines $RE+$ and $RE-$ is 180 volts with condenser $C8$ a 4 microfarad condenser and with the ohmic value of resistance $R3$ 3,000 ohms and of resistance $R7$ 1,000 ohms. Assume further that each of condensers $2C$ to $6C$ inclusive is a 4 microfarad condenser, that each of resistances $2R$ to $6R$ inclusive is a 20 megohm resistance and that the characteristics of each of isolating tubes $2IT$ to $6IT$ inclusive are such that it breaks down at 85 volts and becomes extinguished at 60 volts. Assume also that each of resistances $2R1$ to $6R1$ inclusive is a 30,000 ohm resistance and that each of resistances $2R3$ to $6R3$ inclusive is a 10,000 ohm resistance. Assuming that the ohmic values of resistances $R5$ and $R6$ are 1 and 2 megohms respectively, when power is applied to lines $+$ and $-$ condensers $2C$ to $6C$ inclusive will be charged to 73 volts.

Upon the closure of switches $SE1$ and $SE2$, alternating current voltage is superimposed on the direct current supply lines $+$ and $-$, and the voltage of lines $RE+$ and $RE-$ breaks down the isolating tubes and further charges the condensers as above described. Referring again to the circuits for condenser $2C$ for example, upon the voltage drop across the condenser reaching 120 volts, the voltage drop across isolating tube $2IT$ falls to 60 volts and this tube goes out. The condenser then starts to discharge through resistance $2R$. Due to the high ohmic value of this resistance the discharge takes place relatively slowly. Upon the voltage across the condenser falling to 95 volts the voltage across the isolating tube reaches 85 volts causing the tube to break down. As a result, the condenser immediately recharges whereupon the isolating tube goes out and the condenser discharges again. This discharge, recharge cycle is continuously repeated.

Assume now that contacts $2D3$ are closed. This may occur at any time during any one of the condenser discharge, recharge cycles. The isolating tube is conducting during the recharge portion of a cycle and, if the engagement of contacts $2D3$ occurs then, the condenser voltage reverses the direction of current flow in the isolating tube in effecting the condenser discharge by way of the auxiliary discharge circuit. The isolating tube is not conducting during the discharge portion of a cycle so that, should the engagement of contacts $2D3$ occur then, the condenser voltage causes the isolating tube to break down to effect the condenser discharge by way of the auxiliary discharge circuit. In either case, owing to the fact that resistance $R7$ is of low ohmic value, the potential drop across the condenser drops immediately to the extinction voltage of the isolating tube, namely 60 volts, whereupon the isolating tube goes out. From this point on the condenser discharges slowly into its discharge resistance $2R$ as before. Upon the separation of contacts $2D3$, the condenser is recharged and the discharge, recharge cycles are resumed.

Inasmuch as upon the engagement of contacts $2D3$ the condenser voltage falls immediately to the extinction value of the isolating tube, namely 60 volts, a uniform starting point for the timing operation is had, and as the phase relationship

of the superimposed alternating current grid voltage with respect to the plate voltage is such as to cause the tube to start to conduct near the beginning of the positive portion of each cycle of voltage applied to the plate circuit, uniform timing intervals are had.

When the controlled tube fires, the grid potential becomes positive with respect to the cathode and the negative charge on the condenser is reduced. The values of resistances 2R3 and 2R1 are such as to enable, upon the separation of contacts 2D3, the recharging of the condenser to be effected with the result that the tube is shut off when the grid potential becomes 2 volts negative with respect to the cathode. The condenser is recharged to 120 volts and resumes its discharge, recharge cycles. The operation of the timing circuits for each of the other floors is the same.

The length of each timing operation may be varied by varying the value of the phase shift voltage superimposed on the condenser voltage. This is effected by time control switch TC. The position of the time control switch determines the amount of resistance connected in parallel with the right hand portion of resistance R3. In the top position of the time control switch the switch is open, in the next lower position the parallel resistance is R1 of a certain ohmic value, in the next lower position the parallel resistance is R2 of a lower ohmic value, and in the lowermost position the right hand portion of resistance R3 is short circuited. The net result is to decrease the potential drop across the terminals of resistance R3 as the time control switch is moved from its uppermost to its lowermost position, thereby decreasing the value of the phase shift voltage superimposed on the condenser voltage. The lower the value of the phase shift voltage the longer the time interval before a controlled tube is put in condition to conduct. It has been found that, for the characteristics of the circuits and apparatus previously assumed, as to the values of the resistances and condensers of the phase shift network, resistance R3 may be 1750 ohms with the portion to the left of the connection to the time control switch 450 ohms, resistance R4 5,000 ohms, condenser C3 1 microfarad and condenser C4 .25 microfarad. With resistance R1 1,000 ohms and R2 250 ohms, time intervals approximating 1 minute, 1.5 minutes, 2 minutes and 2.5 minutes are obtained in the consecutive positions respectively of the time control switch TC from top to bottom.

Operation when two or more floor relays have remained operated for more than a certain length of time will now be described. Under such conditions, resistance R9 becomes effective. The ohmic value of resistance R9 is about one-fifth that of the load in the plate circuit of each tube. Assuming the ohmic value of the resistance of the coil of each TR relay to be 2,000 ohms, resistance R9 would be 400 ohms. For such value of resistance R9, a condenser C9 of 250 microfarads would be suitable. When a controlled tube becomes conducting, resistance R9 acts to delay the firing of any other tube, until after the conducting tube is shut off, while condenser C9 acts to cause the next tube to fire to be the one for which the floor relay has been operated longest. In other words, when a plurality of floor relays have been or become operated for the prescribed period, only one controlled tube can be conductive at a time and the order in which they become conductive is the order in

which the floor relays are operated. Resistance R9 and condenser C9 are connected in the common wire leading from line + to the cathodes of the controlled tubes. Thus, when floor relay

5 contacts for one floor have been in engagement for the prescribed length of time to cause the corresponding controlled tube to conduct, current flows through cathode loading resistance R9. This raises the potential of the cathodes of all 10 controlled tubes to block all of such tubes except the one which has fired.

Assume, for example, that the floor relay contacts first engaged for a certain length of time are contacts 2D3. As previously explained, at the expiration of this time period, the negative bias on the control grid of tube 2CT is reduced sufficiently by the condenser discharge to enable the tube to fire. Inasmuch as the plate circuit of tube 2CT is through cathode resistance R9, current flow in this circuit causes a voltage drop across this resistance. As to each of controlled tubes 3CT to 6CT inclusive, this voltage drop raises the potential of the cathode positive with respect to the control grid. This in effect is the same as increasing the negative bias of the grid with respect to the cathode. This blocks tubes 25 3CT to 6CT inclusive so that should one or more other floor relays be operated, in each case when the time interval expires for the tube controlled by such floor relay, the tube does not fire so long as tube 2CT is conducting. For the voltage values and characteristics previously assumed, the voltage drop across resistance R9 when a tube fires would be about 17 volts which means that the condensers of other circuits for which floor relay contacts are engaged would have to discharge an additional 17 volts before the tubes controlled thereby could also fire. As this voltage difference exists in the condenser discharge 30 range where the voltage change is relatively slow, the delay in the firing of other tubes is more than ample to insure the answering of the call and consequent separation of the floor relay contacts controlling the tube which is conducting. As 35 to tube 2CT, when it fires it immediately drains timing condenser 2C as grid resistance 2R3 is of relatively low ohmic value. Thus, although the cathode potential of tube 2CT is raised in a positive direction, the grid potential is also raised in a positive direction at the same time 40 enabling this tube to continue to conduct.

When contacts 2D3 separate, condenser 2C is recharged, as previously described, to shut off tube 2CT. If the time interval for another 45 floor relay has expired, the lowering of the voltage across resistance R9, due to tube 2CT being shut off, causes the tube controlled by this relay to fire, blocking the other tubes. As the time controlled tube 2CT is shut off should there be more than one floor relay operated, the time 50 interval for each of which has expired, condenser C9 delays the lowering of the potential drop across resistance R9 sufficiently to insure the firing of only the tube controlled by the floor relay which has remained operated longest. The delay provided by condenser C9 assures ample 55 time for this controlled tube to ionize and thus fire before the difference in potential between the cathode and grid of another tube can become low enough to cause that tube to fire. Thus, it is seen that only one controlled tube can conduct at a time and that the order in which succeeding tubes become conductive is in the order 60 in which the control operations therefor were initiated.

It is contemplated that many of the features of the invention disclosed may be used in connection with apparatus and circuits different from those specifically described and be applied to systems other than elevator control systems. The timing apparatus and circuits thereof admit of many variations and many apparently widely different embodiments of the invention can be made without departure from the spirit and scope of the invention. It is therefore intended that all matter contained in the above description or shown in the accompanying drawings shall be interpreted as illustrative and not in a limiting sense.

What is claimed is:

1. Electrical timing apparatus comprising; a plurality of electronic tubes, each having a control grid; means for each tube for impressing gradually changing voltage on the grid-cathode of that tube to cause the tube to become conductive upon such voltage reaching a certain value; and means operable upon any one of said tubes becoming conductive to delay the becoming conductive of other tubes, the voltage of said voltage impressing means for which reaches said value while said one tube is conducting.

2. Electrical timing apparatus comprising; a plurality of electronic tubes, each having a control grid; means for each tube for impressing a gradually changing voltage on the grid-cathode of that tube to render the tube conductive upon such voltage reaching a certain value; means operable upon any one of said tubes becoming conductive to delay the becoming conductive of other tubes, the voltage of said voltage impressing means for which reaches said value until said one tube is shut-off; and means for causing said tubes to be rendered conductive in the order in which the voltage of their respective voltage impressing means reached said value.

3. Electrical timing apparatus comprising; a plurality of electronic tubes, each having a control grid; means for each tube operable upon the expiration of a certain time interval to apply a potential to the grid-cathode of the tube of a value to cause the tube to fire; means for each tube for shutting off the tube; means operable upon the firing of any one of said tubes to delay the firing of other tubes the time intervals for which have expired until after said one tube is shut off; and means operable when the time interval for two or more tubes has expired when a tube which has fired is shut off to cause the next tube to fire to be the one the time interval for which expired first.

4. Electrical timing apparatus comprising; a plurality of electronic tubes, each having a control grid; means for each tube for raising the potential of the grid with respect to cathode of that tube to a value to render the tube conductive; and means operable, upon any one of said tubes becoming conductive, to raise the potential of the cathodes of the other tubes with respect to grids and upon said one tube becoming non-conductive to delay the decrease in said potential of the cathodes with respect to grids of such other tubes.

5. Electrical timing apparatus comprising; a plurality of electronic tubes, each having a control grid; means for each tube for controlling the potential of the grid of that tube with respect to the cathode; a resistance common to said tubes connected so that upon any one of said tubes becoming conductive it provides a potential drop to raise the potential of the cathodes of the other

tubes with respect to grids; and capacitance for delaying the decrease in potential drop across said resistance upon a tube which has been conducting becoming non-conductive.

5 6. Electrical timing apparatus comprising; a plurality of gas filled electronic tubes, each having a control grid; means for each tube for controlling the potential of the grid of that tube with respect to the cathode to render the tubes conductive; a conductor common to the plate circuits of the tubes leading to the cathodes of the tubes; a resistance connected in said conductor adapted, upon any one of said tubes becoming conducting, to provide a potential drop to raise the potential

15 of the cathodes of the other tubes with respect to grids; and capacitance for delaying the decrease in potential drop across said resistance upon a tube which has been conducting becoming non-conductive.

20 7. Electrical timing apparatus comprising; a plurality of gas filled hot cathode electronic tubes, each having a control grid; a condenser for each tube; a discharge resistance for each condenser; means for controlling the charging and discharging of the condensers, the grid-cathode circuit of each tube being connected across the condenser provided for that tube to place a negative potential on the grid with respect to cathode to block the tube when the condenser is charged and to

25 render the tube conducting when the condenser has discharged to a certain voltage value; a resistance common to said tubes connected in the plate circuits of the tubes on the cathode side adapted upon any tube becoming conducting to provide a potential drop to raise the potential

30 of the cathodes of the other tubes with respect to grids; and a condenser connected across said resistance to delay the decrease in potential drop across said resistance upon a tube which has been conducting becoming non-conductive.

40 8. Electrical timing apparatus comprising; a plurality of gas filled hot cathode electronic tubes, each having a control grid; a condenser for each tube; a discharge resistance for each condenser; means for charging the condensers, the grid-cathode circuit of each tube being connected across the condenser provided for that tube to place a negative potential on the grid with respect to cathode to block the tube when the condenser

45 is charged and to render the tube conducting when the condenser has discharged to a certain voltage value; a source of current; a plurality of plate circuits, one for each tube, said plate circuits including conductors common to said tubes connected to said source; a plurality of electrical loads, one for each tube, connected in the plate circuits of the respective tubes; a resistance common to said tubes connected in series therewith in that one of said conductors leading to the

50 cathodes of the tubes adapted upon any tube becoming conducting to provide a potential drop to raise the potential of the cathodes of the other tubes with respect to grids to delay any one of them being rendered conductive when the condenser provided therefor discharges to said certain voltage value; and a condenser connected across said resistance to delay the decrease in potential drop across said resistance upon a tube which has been conducting becoming non-conductive

55 to cause, when condensers for two or more other tubes have discharged to or below said certain voltage value, that one of such tubes, the condenser for which has been discharging longest, to become conducting.

70 9. Electrical timing apparatus comprising; a

source of direct current; a gas filled electronic tube having a control grid; means for applying direct current voltage from said direct current source to the anode-cathode circuit of the tube; a source of alternating current; means for superimposing alternating current voltage from said alternating current source on said direct current voltage applied to said anode-cathode circuit; a condenser connected across the grid-cathode circuit of the tube; means for charging said condenser to place a potential on the grid with respect to the cathode to block the tube; a discharge resistance connected across said condenser for effecting a delayed decrease in the voltage of said condenser upon discontinuance of the charging thereof; a phase shift network connected to said alternating current source for superimposing on the voltage applied by said condenser to said grid-cathode circuit alternating current voltage of a phase relationship with respect to the voltage applied to said anode-cathode circuit to render the tube initially conductive near the beginning of the positive portion of an anode-cathode voltage cycle upon the condenser discharging to a

certain voltage value; and means for varying the value of said superimposed alternating current grid-cathode voltage to vary the time interval from the time the condenser starts to discharge until the tube becomes conductive.
